UNITED STATES PATENT OFFICE.

DARRELL FRANK DYKE, OF CHICAGO, ILLINOIS, ASSIGNOR TO THE SENG COMPANY, OF CHICAGO, ILLINOIS, A CORPORATION OF ILLINOIS.

BEDSTEAD CORNER-FASTENING.

1,137,260.

Specification of Letters Patent. Patented Apr. 27, 1915.

Application filed September 4, 1913. Serial No. 788,074.

To all whom it may concern:

Be it known that I, DARRELL FRANK DYKE, a citizen of the United States, residing at Chicago, in the county of Cook and State of Illinois, have invented new and useful Improvements in Bedstead Corner-Fastenings, of which the following is a specification, reference being had to the accompanying drawings, forming a part thereof.

10 The purpose of this invention is to provide an improved construction for a bedstead corner fastening.

15 It consists in the elements and features of construction shown and described as indicated in the claims.

20 In the drawings:—Figure 1 is an inside perspective view of a bedstead corner embodying this invention. Fig. 2 is a vertical transverse section at the line, 2—2, on Fig. 1, 25 showing the side rail in one of two positions for which the device is adapted. Fig. 3 is a view similar to Fig. 2, showing the side rail in the other of the two positions for which the device is adapted. Fig. 4 is a vertical section at the line, 4—4, on Fig. 2. Fig. 5 is a section at the line, 5—5, on Fig. 2. Fig. 6 is a plan view of a blank from which the main element of the device is formed.

25 In the structure shown in the drawings, A 30 represents the corner post of a bedstead.

B is the corner post fitting or bracket secured to the bed post and adapted for receiving and holding the side rail, C, of the bed, and having also lugs for bolting it to the transverse rail, D. This bracket fitting is made from a blank shown in Fig. 6, of which the wings, 1 and 2, are folded at the four parallel horizontal lines, b¹, b², b³ and b⁴, to lap upon each other at one side and 40 form a square socket for receiving the end of the side rail. The wings, 3 and 4, are folded at vertical lines, b⁵ and b⁶, so as to lap upon each other at the parts, 3^a and 4^a, to form the back or vertical member of the 45 bracket for seating against the post to which the entire bracket is bound by bolts, 5 and 6, taken through said lapped portions, 3^a and 4^a, and through the post, and a reinforcing washer plate, 7, within the post. Preferably 50 the bolts are inserted from within the post outward through the parts mentioned, and secured by nuts, 8 and 9 upon their ends which protrude through the lapped parts, 3^a and 4^a, one within the square socket and 55 the other below the same, said folded wings,

3 and 4, being cut so as to extend below the folding lines, b³ and b⁴, of the square socket. The outer lapped terminal portion, 2^a, of the wing, 2, has two terminal lugs, 2^b and 2^c, projecting in the blanks respectively, at the end and at the side of said outer-lapped portion, 2^a, and adapted to be folded at lines, b⁷ and b⁸, respectively, at right angles to each other, so that said lugs project, as seen clearly in Fig. 1, in planes 60 at right angles to each other, one horizontal, and the other vertical, transversely of the length of the square socket which receives the side rail, whereby said lugs are in position to afford lodgment and securement for 65 the transverse rail, D, which has its flanges bolted to said lugs.

70 Each end of the side rail, C, is provided at the portion of its length which can extend in the square socket, with a brace clamp, 12, 75 which in general is positioned diagonally or obliquely across the angle of the side rail, but sprung or bent outward so as to present an arch form to any pressure operating to force it toward the angle or toward either 80 flange of the side rail. The lateral edges of this brace clamp are bent to form foot flanges, 11, 11, for seating upon the flanges, respectively, of the side rail. A binding screw, 13, with a wing head, adapting it to be 85 operated by hand, is set through the inner side of the square housing formed by the lapped ends of the two lugs, 1 and 2, and the brace clamp, 12, has preferably slightly sunken seats, 12^a, 12^b, one at the position to 90 seat the end of the clamping screw when the side rail is inserted in the socket with horizontal flange upward, and the other at position to seat the screw when the side rail is inserted with the horizontal flange at the 95 bottom. The brace clamp, 12, is retained loosely in the angle of the side rail, by headed studs or posts, 14, projecting from the two flanges, respectively, of the side rail, 100 so that the pressure of the clamping bolt is transmitted to both flanges and causes the side rail to be bound snugly into the angle of the socket and held rigidly, not only against withdrawal, but also against twisting or turning in the socket. 105

I claim:—

110 1. A bed corner fitting comprising a rectangular socket, in combination with an angle-iron side rail adapted to be inserted in the socket; an obliquely-extending brace

clamp held loosely in the angle of the side rail at the end portion thereof which enters the socket, and a clamping bolt set through one side of the socket for impinging upon 5 said oblique brace clamp to force the same against the flanges of the side rail and seat the latter in the corner of the socket.

2. A bedstead corner fitting comprising a bracket member adapted to be secured to 10 the corner post and having a rectangular socket and a clamping screw set through the inner side of said socket protruding into the cavity thereof, in combination with an angle-iron side rail, adapted to have its end entered in the socket; an oblique brace clamp 15 lodged and loosely retained in the angle of the side rail at said end portion, said brace clamp being bent outwardly opposite the angle of the side rail; and provided with two 20 seats for the end of the clamping bolt at positions respectively for seating said bolt when the side rail is inserted in the socket with the horizontal flange at the top, and when it is inserted with said flange at the 25 bottom.

3. A bedstead corner fitting consisting of a bracket made of a single piece of metal plate folded at not less than three parallel lines to form four encompassing walls of a 30 rectangular socket, presenting, for receiving

a side rail endwise, an opening equal to the cross-sectional area of the socket back of said opening, and further folded at a line at right angles to said parallel lines to form a vertical back plate for mounting the bracket 35 on the post, and having lugs projecting at right angles to each other and folded one at a line parallel to said three parallel lines, and the other at a line parallel to the line of folding of the back plate, whereby said lugs at right angles to each other both project at right angles to the length of the rectangular socket, for securing of a cross rail.

4. A bedstead corner fitting made of one 45 piece of metal plate, having lugs folded to lap each other to form a rectangular socket, and riveted together at their lap, and other lugs folded to lap each other and form a 50 vertical channel at the inner end of the rectangular socket, and bolts which bind them together at their lap adapted also for securing the fitting to the post.

In testimony whereof, I have hereunto set my hand at Chicago, Illinois, this 30 day of 55 August, 1913.

D. FRANK DYKE.
